UNITED STATES PATENT OFFICE.

WILBUR W. QUINN, OF GOSHEN, INDIANA, ASSIGNOR OF ONE-HALF TO NATIONAL CHEMICAL COMPANY, OF SYRACUSE, NEW YORK, A CORPORATION OF NEW YORK.

LAUNDRY-CONVEYER DROP.

1,019,086.

Specification of Letters Patent.

Patented Mar. 5, 1912.

Application filed November 18, 1910. Serial No. 593,091.

To all whom it may concern:

Be it known that I, WILBUR W. QUINN, of Goshen, in the county of Elkhart, in the State of Indiana, have invented new and useful Improvements in Laundry-Conveyer Drops, of which the following, taken in connection with the accompanying drawings, is a full, clear, and exact description.

This invention relates to certain improvements in laundry conveyer drops adapted to be used in connection with endless conveyer chains for conveying more or less damp laundry articles through and from a suitable drying room and automatically and successively depositing them into a suitable receptacle immediately upon their exit from such drying room. In this class of carriers the conveyer chains are mounted upon suitable horizontally disposed drums located a considerable distance apart in such manner as to cause a large portion thereof to travel through the drying room while other portions are disposed at the exterior of the drying room. The conveyer is moved at a comparatively slow rate of speed to afford ample time for the complete drying of the laundried articles while traveling through the drier and at the same time permits the attendant to place the damp articles on the hangers at the exterior of the drier away from the heat so that the operation of drying the articles and reloading the conveyer may be practically continuous.

The carriers upon which the laundry articles are directly supported are suspended preferably uniform distances apart from the underside of the chain and are preferably attached to pendant rods or standards integral with one of the links and my present invention relates more particularly to the carrier.

I am aware that various forms of carriers are now in use some of which are adapted to receive and support collars, cuffs and similar articles having button holes therein for receiving the projecting member or members on the carrier while others are provided with coacting gripping members between which the articles are held by fric-

tion while still others combine two forms of retaining elements in a single carrier but in all of these devices with which I am familiar the supporting rods which are adapted to pass through button holes or other apertured garments for retaining the same on the conveyer during their transit to the drier are offset or angular longitudinally to prevent the articles from slipping from their supporting rods and it frequently happens that projecting threads or mutilated parts of the dampened article will become wound around and dried upon the rods while passing through the drier so that it is practically impossible to automatically withdraw the studs from the button holes of such articles upon their exit from the drier without more or less mutilation of such article owing to the angularity of the supporting rods. Furthermore it has been found that where springs are employed to close the movable gripping members with sufficient force to frictionally retain the articles on the carrier, considerable power is required to release the movable jaws to discharge the dried articles as they emerge from the drier, thereby subjecting the conveyer and automatic tripping mechanism to considerable unnecessary strain and at the same time rendering the tripping operation more or less unreliable.

The main objects therefore of my invention are: First—to make the draw rods or supports for collars, cuffs and similar articles straight from end to end so that they may be more readily withdrawn from the button holes and also to guide said rods in suitable strippers fitting more or less closely thereon so as to effectively remove any loose threads or mutilated parts of the article which may become dried on the rod. Second—to provide each carrier with extra guards for preventing accidental displacement of the articles which may be mounted on the rods during their passage through the drier. Third—to provide the carrier with gravity closing gripping jaws mounted in such manner that the weight of the articles between the coacting stops or jaws will tend

to tighten the grip of the movable jaws thereon and at the same time permitting the movable jaws to be positively but easily released under light contact with the tripping device.

5 A still further object is to provide the coacting tips of the jaws with noncorrodible sections of glass, porcelain or equivalent material capable of withstanding the heat. 10 of the drying room and at the same time preventing injury by soiling and preventing injury to the garment.

15 Another object is to provide yielding tripping devices for the jaws to reduce the liability of breakage to a minimum in case the movable jaws should become set in their closed positions or fail to open from any other cause by contact with said tripping devices.

20 Another object is to provide means for preventing the laundry articles from becoming caught or wrapped upon the tips of the movable jaws to such an extent as to prevent the automatic discharge of the 25 dried articles therefrom.

Other objects and uses relating to specific parts of the device will be brought out in the following description.

In the drawings Figure 1 is an elevation of 30 a portion of a laundry conveyer and section of a portion of a drying room showing my improved carriers, and tripping device for releasing the articles upon their exit from the drying room. Fig. 2 is a top plan of one of 35 the detached carriers showing its hanger rod in section, said carrier being shown as just entering the tripping device indicated by dotted lines. Figs. 3 and 4 are front elevations partly in section of the same carrier, 40 the movable jaws being shown in their open position in Fig. 3 and in their closed position in Fig. 4, portions of the tripping device being shown in section in both views. Fig. 5 is an edge view of the carrier. Figs. 45 6 and 7 are enlarged detail sectional views of a portion of one of the movable jaws and a portion of one of the fixed jaws. Figs. 8 and 9 are transverse sectional views taken on lines 8—8, Fig. 6 and 9—9 Fig. 7.

50 In Fig. 1 I have shown one end of a drying room —1— as provided with an exit opening —2— through which travels a horizontally disposed conveyer chain —3— having certain of its links provided with 55 pendant hanger arms —4— spaced a uniform distance apart and each supporting a clothes carrier —5— forming the main subject matter of my invention. A suitable trip or cam track —6— is mounted upon a 60 supporting frame —7— just outside of the drier —1— for releasing the gripping jaws of the carrier hereinafter described and permitting the dry articles —A— to gravitate into an underlying receptacle 65 —8—. Each carrier comprises a main sup-

porting frame —9— having fixed jaws —10— and movable jaws —11— the latter being preferably made in the form of bell crank levers pivoted at —12— to the main supporting frame —9— and having their inner arms —13— projecting upwardly some distance above their pivots and through elongated slots —14— in the main supporting frame. The upper portion of the frame —9— is disposed in a substantially horizontal position and provided with a central tapering socket —15— for receiving a correspondingly tapered lower end of the adjacent hanger rod —4—, these parts being held in operative connection by 70 a clamping bolt —16— which may be a cotter key to permit the carrier to be readily removed from or reattached to the hanger when desired. The opposite ends of the frame —9— are curved downwardly and inwardly and are provided with sockets —17— opening from their lower ends and inner sides for receiving suitable contact tips —18— of glass, porcelain or other noncorrodible material, these tips being 75 held in place by cotter keys —19— or equivalent fastening means capable of being easily removed to permit the removal or reinsertion of the tips —18—. The central portion of the frame —9— is provided with a pendant arm —20— spaced some distance apart from the inwardly curved jaws —10— to allow ample room for the insertion of the articles between the jaws and also for the free play of the movable jaws, said pendant portion —20— being provided with vertically slotted ears —21— in which the movable jaws —11— are pivoted.

The free ends of the movable jaws —11— 105 are provided with contact tips —22— of porcelain, glass or other non-corrodible material secured to the corresponding ends of their respective supporting levers by pins —23— and adapted to play between the tips —18— and superposed stop shoulders —24— on the main supporting frame —9—. These movable jaws project outwardly or laterally in opposite directions from their supporting pivots —12— and are weighted sufficiently 110 to cause them to gravitate to their closed positions so that their tips —22— will engage the tips —18— and thereby grip between them any article which may be desired to pass through the drier, the weight of said 115 article and friction serving to draw the jaws into closer gripping engagement therewith and prevent as far as practicable any liability of said articles becoming detached in transit through the drier. The stop shoulders —24— also serve to limit the upward movement of the articles when being inserted between the jaws to prevent them from overhanging upon the upper sides of the movable jaws so that when dried and 120 125 130

released by the opening of the jaws through the medium of the tripping mechanism will readily gravitate into the receptacle —8— without liability of becoming wrapped around or caught by the jaws. The upwardly projecting arms —13— of the movable jaws are provided with laterally and outwardly projecting pins or rods —26— having their inner ends pivoted thereto and their outer ends passing through and guided in apertured ears —27— on the outer ends of the main supporting frame —9—, said pins being of sufficient length to project some distance outwardly and beyond the apertured ears —27— when the jaws are closed for entering the button holes of collars, cuffs and similar articles and thereby retaining said articles on the carrier during their passage through the drier. These pins or rods —26— are preferably straight from end to end and formed of easily bendable material such as soft wire of sufficient strength to support the articles without bending and at the same time capable of being straightened in case they should become bent in passing back and forth through the apertured lugs —27—.

The apertures in the lugs —27— are of substantially the same size as the rods or pins —26— with just sufficient clearance to permit the free movement of the rods or pins therethrough for the purpose not only of straightening the rods or pins in case they should become bent but also of more effectively stripping the laundried articles therefrom as they are withdrawn inwardly under the action of the tripping mechanism. In order that these articles may be more positively held upon the pins against accidental displacement while passing through the drier, I provide the adjacent ends of the frame —9— with open guard-loops —28— preferably consisting of wires rigidly secured to the frame and having their open sides facing in a direction opposite to the direction of movement of the conveyer so that when the pins —26— are withdrawn under the action of the tripping mechanism, the articles previously supported thereby will readily fall or gravitate into the underlying receptacle —8—, the guards —28— being located some distance below the protruding ends of the pins —26—.

The cam tracks or tripping mechanisms —6— are disposed in the path of movement of the outer edges of the upper portions of the arms —13— just outside of the discharge end of the drier and are converged forwardly in the direction of movement of the carrier but are preferably supported in such manner as to yield laterally in case the jaws should become caught and fail to open from any cause. For this purpose suitable springs —30— are interposed between the ends of the track —6— and their supporting mem-

bers —7— of sufficient tension to cause the tracks to open the jaws without yielding but capable of yielding in case the jaws should become caught or fail to open, thereby relieving the conveyer from excessive strains. 70

The conveyer —3— travels at a very slow rate of speed which enables the attendant to successively place button-holed articles upon the protruding ends of the pins —26— and within the loops —28— and to also insert portions of other articles between the coacting sets of jaws —10— and —11— on the portions of the conveyer outside of the drying room, the gravity of the movable jaws serving to hold them in their closed positions with the pins —26— protruding some distance outwardly beyond their guide ears —27—. The articles thus supported upon the carriers are then conveyed slowly through the drying room and returned 80 through the opening —2— to the exterior thereof where the arms —13— of the movable gripping jaws encounter and are opened by contact with the tripping cams —6— thereby releasing said articles from between 90 the coacting sets of jaws —10— and —11— and also withdrawing the pins —26— backwardly through the guides —27— and also the articles which they previously supported, the ears —27— serving as strippers to effectively remove any portions of the articles which may have become dried on the pins, thus allowing said articles to drop into the underlying receptacle —8— after which the emptied carriers are refilled with more or 100 less damp articles to be dried.

What I claim is:

1. A drop-carrier for endless conveyers comprising a frame having apertured stripper guides and straight pins movable back and forth in the apertures in said guides, the apertures and pins being of substantially the same cross-sectional size. 105

2. A drop-carrier for endless conveyers comprising a frame, rock arms on the frame, straight supporting pins connected to and movable with the rock arms, stripper guides fitting closely around the pins and secured to the frame, and guard-loops on the frame for retaining articles on the pins. 110

3. A drop-carrier for endless conveyers comprising a frame having fixed jaws spaced some distance apart, levers pivoted to the frame and provided with movable jaws co-acting with the first named jaws, stops on the frame for limiting the upward movement of the movable jaws, pins pivoted to the levers and movable therewith, stripper guides for the pins, and guards on the frame for holding articles on the pins. 120

4. A drop-carrier for endless conveyers comprising a frame having fixed jaws spaced some distance apart, levers pivoted to the frame and provided with movable jaws co-acting with the first named jaws, stops on 130

the frame for limiting the upward movement of the movable jaws, pins pivoted to the levers and movable therewith, stripper guides for the pins.

5. A drop-carrier for endless conveyers comprising a frame having fixed jaws spaced same distance apart, levers pivoted to the frame and provided with movable jaws co-acting with the first named jaws, pins piv-

oted to the levers and movable therewith, stripper guides for the pins.

In witness whereof I have hereunto set my hand on this 7th day of November 1910.
